ABSTRACT OF THE DISCLOSURE

A toilet article comprising a tube of toilet preparation and an aerosol dispenser, either or both of which are provided with cooperating attaching means enabling them to be attached together in at least a position of non-use. The attaching means may be formed in the cap of the tube or on the top or bottom of the dispenser.

BACKGROUND OF THE INVENTION

The present invention relates to a toilet article, and more particularly to a combination of a tube of toilet preparation and an aerosol dispenser.

It is an object of the present invention to provide a combination of a tube of toilet preparation and an aerosol dispenser with attaching means which minimises the risk of mislaying the dispenser.

It is another object of the invention to provide a combination of a tube of toilet preparation with an aerosol dispenser with attaching means which provides an attractive sales package.

Other objects and advantages of the invention will be apparent from the detailed description below.

SUMMARY OF THE INVENTION

The toilet article according to the invention comprises, in combination, two distinct elements, namely a tube of toilet preparation and an aerosol dispenser, and attaching means enabling the attaching of said two elements one to the other at least when in a position of non-use.

The invention will now be described more fully with reference to the accompanying drawings which show, purely by way of illustrative but non-limiting example, one embodiment of a toilet article in accordance with the invention.

BRIEF DESCRIPTION OF THE DRAWING

FIG. 1 is a schematic view in elevation, with a partial section, of the toilet article in a position of non-use.

FIG. 2 is a view similar to FIG. 1, showing the toilet article in the use position of the dispenser.

FIG. 3 is a modification of the toilet article shown in FIG. 1 wherein the side wall of the tube is extended to provide a skirt for receiving the top of the dispenser which provides a closure cap for the tube.

FIG. 4 is a modification of the toilet article shown in FIG. 2 wherein the side wall of the tube is extended to provide a skirt for receiving the bottom of the dispenser which provides a closure cap for the tube.

2

**DESCRIPTION OF THE PREFERRED
EMBODIMENT**

Referring to the drawings, the toilet article illustrated has two distinct principal elements, namely a tube of toothpaste 1 and an aerosol dispenser 2. Attaching means permit attachment of the two elements 1 and 2 one to the other when not in use. In the embodiment shown in the drawing, the cap 3 of the toothpaste tube 1 has an extension 4 in the form of a skirt, of flexible material, for example of flexible plastic material. The cross section of the skirt 4 corresponds to that of the body of the dispenser 2. Accordingly, the latter can be engaged in the skirt 4 either by its top 5 (as shown in FIG. 1), or by its bottom 6 (see FIG. 2).

This specially shaped cap 3 thus affords means permitting attachment of the tube of toothpaste 1 and the dispenser 2 one to the other, so as to provide a particularly attractive sales package. FIG. 2 shows that the dispenser 2 can also be used while it is attached by its body to the cap 3 of the tube 1, which on occasion facilitates keeping the dispenser 2 handy if it is small in size.

It will be apparent that numerous variations of the embodiment described above could be devised without departing from the essential concept of the invention. Thus the cap 3 could be formed directly in the bottom 6 of the dispenser 2 as shown in FIG. 4. It would be sufficient for the bottom 6 to have a tapped hole 8 having a pitch corresponding to that of the threaded tip 7 of the tube of toothpaste 1. However, this embodiment would necessitate the presence of a cap for the protection of the top 5 of the dispenser 2. One could, with equal facility, make the top 5 of the dispenser 2 in such a way that it, in itself, provides the cap of the tube 1 as shown in FIG. 3 by enlarging the nozzle 9 and providing it with a tapped hole 10.

Conversely to the embodiment shown, the cap of the dispenser 2 could have a shape enabling it to be engaged by the neck of the tube 1, whether or not the latter is provided with a special closure cap.

The dispenser 2 may comprise an aerosol container which could contain either liquid dentifrice or a deodorant or disinfectant product for the mouth and throat or even a disinfectant for toothbrushes before use.

Having particularly described the invention, it is to be understood that it is not to be considered limited to the details herein set forth and that various modifications will be apparent to one skilled in the art which are within the scope of the appended claims.

I claim:

1. A toilet article, comprising, in combination, two separate elements, namely a tube of toilet preparation and an aerosol dispenser, means for attaching said two elements one to the other at least when in a position of non-use, said attaching means comprising a closure cap for said tube including a skirt of flexible material corresponding in cross section to the cross section of the dispenser, such that said dispenser can be attached to said skirt either by its top or by its bottom.

60 2. A toilet article, comprising, in combination, two separate elements, namely a tube of toilet preparation and an aerosol dispenser, means for attaching said two elements one to the other at least when in a position of non-use, said attaching means comprising a skirt of flexible material, said skirt being an extension of said

tube, the cross section of said skirt corresponding to the cross section of the dispenser such that the dispenser can be attached to said skirt either by its head or its base, a part of said dispenser comprising a closure cap for said tube.
